1

This invention relates to the art of atomizing liquids, including solutions, emulsions and suspensions, by the formation of a liquid film which is disrupted and thus divided into fine droplets by means of an atomizing gas stream. The invention finds particular although not exclusive application in situations wherein it is desired to atomize liquids into small droplets, and wherein it is desirable that the diameters of the droplets be of greater uniformity than is possible with other simple atomizing devices and methods and/or wherein the complication of moving parts is to be avoided. Thus, the invention may be applied to the spraying of biocides from aeroplanes or from the ground, in driers, in chemical reactors wherein small drops of liquid are to be contacted with a gaseous reagent, such as air, oxygen, halogens, etc. in oil burners, carburetors and atomizers for internal combustion engines.

The atomization of liquids by atomizing gas currents is often effected by causing a film of liquid to be formed on a rotating body having a surface of revolution, e. g., a rotating disc or cup, to which the liquid is supplied at or near the axis of rotation, the liquid moving outwards from said axis as a film adhering to the surface of the rotating body; upon reaching the periphery of the body it is discharged therefrom as a film or as liquid filaments and caught by a stream of atomizing gas which divides the film or filaments into fine drops. In such an arrangement the friction between the rotating body and the liquid produces the force necessary for accelerating the movement of the liquid outwards towards the circumference, thereby causing a reduction in the thickness of the liquid film as it approaches the circumference. This reduction in the thickness of the film is further due to the fact that as the liquid moves outwards the surface of the disc that is to be covered by a given quantity of liquid becomes larger, this area being directly proportional to the radius on which the liquid moves when the radial velocity of the liquid is constant. Such a technique requires rapidly rotating parts and motive power for driving them; moreover, the size of the resulting drops is often far from uniform because the thickness of the liquid film at the periphery has a tendency to be non-uniform, this being aggravated when even minute irregularities occur on the surface of the disc or cap or particles of adventitious solids are deposited on the surface.

The droplet diameter with the rotating disc is inversely proportional to the circumferential speed of the disc (diameter of the disc times rotating speed).

2

If, instead of a rotating disc or cup, a stationary liquid distributing body, such as a round disc or cone, were to be used, to which the liquid is supplied at or near the center in such a manner that at that point the liquid acquires a certain radial velocity, then the liquid, if friction and surface tension were to play no part, would retain this radial velocity up to the circumference and the thickness of the film in an outward direction would diminish and be always in inverse proportion to the radius. The friction occurring between the stationary body and the liquid, however, causes a significant reduction in the radial velocity; this causes the radial velocity at the circumference of the disc or cone to be reduced materially. The consequence is that the thickness of the film is substantially greater than if there were no friction, so that it is difficult to divide by means of a gas stream the liquid discharged from the stationary body into droplets having diameters of such small values as are required for many purposes. Moreover, in order to maintain an adequate radial velocity of the liquid moving on the stationary liquid distributing body and, consequently, a uniform distribution of the liquid over the circumference of the body, the diameter of the body must be kept small.

With a stationary disc the thinness of the liquid film emerging from the disc and consequently the droplet diameter resulting from breaking up such a film by an air stream is theoretically inversely proportional to the disc diameter. For the reasons mentioned above, however, (friction losses and even distribution), the disc must be small, which, however, implies that the film is not extended over a large area before reaching the periphery and therefore remains thicker than is desirable for a subdivision into fine droplets.

It is an object of the invention to provide an improved method and apparatus for atomizing liquids by means of an atomizing gas stream wherein the liquid film is thinned by radial flow without being subjected to such frictional forces prior to being disrupted by the atomizing gas.

45 A further object is to provide an improved method and apparatus for atomizing liquids by disrupting a film thereof with an atomizing gas that does not require the use of a rotating body.

The instant invention is based on the concept that the film of liquid discharged from a liquid distributing body, such as a stationary disc, must be given an opportunity to be thinned further by rendering possible a continued radial movement 55 of the liquid film after leaving the body and

before being engaged by the atomizing gas stream. In this continued radial movement the liquid is then no longer hampered by the friction with the disc, but only by the much smaller forces due to friction with the substantially quiescent gas through which the film moves and the surface tension. The liquid consequently retains practically the radial speed it had when leaving the distributing body, on account of which the thickness of the film reduces further to assume a thickness that is approximately inversely proportional to the radius measured from the center of the body. To attain this it is necessary, however, to prevent atomizing gas current, which is to divide the liquid film into drops, from attacking the film as soon as it leaves the body; the gas should not encounter this film before the latter has undergone radial flow beyond the periphery of the distributing body and has acquired the thinness indicated by the drop size desired.

According to the invention the liquid is supplied to an intermediate part, preferably a point substantially at the center, of a liquid distributing body that has, preferably, a circular outline in a manner to impart to different portions of the liquid divergent, preferably radial velocities along said surface, and is thereafter flowed outwardly as a film on the surface of the body and discharged from the periphery thereof as a divergent film; the film is then passed outwardly in divergent directions through a substantially quiescent space for a distance necessary to effect the desired thinning and is, upon emergence from the quiescent space, attacked by a current of atomizing gas that flows more or less perpendicular to the liquid film. The atomizing gas flow is conducted in such a manner that the gas passes the distributing body only at some distance spaced radially outwardly from the periphery of the body and thus encounters the liquid film at some distance from the latter. This can be effected in a simple manner by arranging ahead of the discharge edge of the distributing body, (i. e., upstream with regard to the direction of the atomizing gas flow) a gas deflector or screen of a larger diameter than that of the distributing body, to provide an annular quiescent thinning space behind the deflector. The surface of the liquid distributor on which the liquid film is formed may be directed either upstream or downstream with respect to the direction of flow of the atomizing gas. The invention will be described with reference to the preferred embodiment wherein the liquid distributing body is a stationary body onto which the liquid is directed to form a liquid film traveling radially outwardly and wherein the distributing body has a circular periphery forming the discharge edge, but neither of these two limitations is in every case essential, it being evident that any suitable means may be employed to impart a radial velocity to the liquid supplied at the center of the distributing body, and that the geometrical shape of the outer edge or periphery of the latter may be varied in accordance with the distribution of liquid at the center towards different radial directions. The surface of the distributing body is advantageously a surface of revolution, e. g., a flat or conical surface. Greatest uniformity of drop sizes is attained by using a liquid distributor with a surface having a circular margin and supplying the liquid to the center thereof as a film that flows uniformly in all radial directions.

Having thus indicated the nature of the inven-

tion in general terms, the invention will be described with reference to the accompanying drawings forming a part of this specification and illustrating certain preferred embodiments thereof, wherein:

Figs. 1 and 2 are a longitudinal, axial section and an end elevation view, respectively, of one embodiment suitable for application to an aeroplane;

Fig. 3 is a longitudinal, axial section view of a modified construction suitable for like application; and

Fig. 4 is a vertical, axial section view of a third form suitable for use with a blower to supply atomizing gas, parts being shown in elevation.

The device of Figs. 1 and 2 is supported by a supply pipe 10 which may be secured to a moving object such as a vehicle or an aeroplane which may be given a substantial velocity relative to the ambient air and connected to a source of liquid to be atomized, not shown. An annular disc 11 of circular outline, forming a gas deflector, is fixed to front end of the pipe and a stationary flat smaller liquid distributing disc 12, also of circular outline and forming a stationary liquid distributing body is mounted a suitable distance from the air deflector. The distributing body may be mounted by being bolted to a support 13 that is supported by streamlined arms 14 from a threaded ring 15 that can be adjusted axially on a threaded collar 16 fixed to the pipe, a lock nut 17 being provided to retain the ring 15.

Of course the liquid distributing disc 12 can, instead of by outside supporting arms 14, be carried by an inside supporting rod, fixed centrally to the disc 12, situated in the centre of the liquid stream and fixed with its other end to the inside of the supply pipe 10 somewhere upstream away from the orifice of the pipe 10.

The liquid to be atomized is flowed through the pipe 10 with a velocity sufficient to flow beyond the end of the pipe and to form a film of liquid on the disc 12 that flows evenly in all radial directions. The liquid velocity should be adequate to effect distribution but not so great as to produce rebounding drops or splash. This film flows outwardly to the perimeter of the disc 12 and continues to move in divergent radial directions beyond the perimeter as a gradually thinning film. The velocity is advantageously chosen so that the film discharged from the disc retains its cohesion at least until the film attains a diameter equal to that of the deflector 11. The stream of atomizing gas, indicated by the arrows marked 18, flows relatively to the atomizer from left to right; it may be generated, for example, by movement of the vehicle or aeroplane on which the atomizer is fitted toward the left as seen in Fig. 1, or by a fan or the like, as described hereinafter. The deflector 11, having a greater diameter than distributing disc 12, prevents the atomizing gas stream 18 from reaching the disc 12 or immediate vicinity thereof and forms an annular, substantially quiescent thinning space to the downstream side thereof. As a consequence the liquid film is not seized by the gas stream until it reaches a circular line having a diameter almost as great as that of the deflector 11 and indicated by the number 19, but flows through the substantially quiescent thinning space containing substantially quiescent gas after discharge from the distributing disc and until reaching the circular line 19. Upon passing radially beyond the latter the film

is attacked by the gas current and disrupted into

fine droplets which are entrained by the gas stream, as indicated by the number 20.

It is evident that the size of these droplets may be controlled by selecting a deflector disc 11 of suitable diameter, and that the relation between the diameters of the discs 11 and 12 may be selected in accordance with the type of atomization desired and other conditions, such as the properties of the liquid (density, viscosity, surface tension) and of the atomizing gas. The dimensions will, further, depend upon the rate at which liquid is to be atomized. By way of specific example, in one arrangement according to Figs. 1 and 2, the mouth of the pipe 10 had a diameter of about 5 mm., the liquid distributing disc 12 had a diameter of about 10 mm., the gas deflector disc had a diameter of about 40 mm., and the distance between these discs was about 5 mm. A liquid having the nature of gas oil was atomized at a rate of 500 liters per hour and the air was used as the atomizing gas, the air velocity relative to the atomizer being 100 km. per hour and generated by moving the atomizer through the atmosphere. An adequate atomization was attained and the drops had diameters of from about 150 to 200 microns. In most cases the substantially quiescent thinning space extends through a radial distance that is at least half as great as the radius of the surface of the liquid distributor, i. e., the diameter of the disc 11 is at least 1.5 as great as that of the disc 12. In general, it can be stated that in an arrangement according to Figs. 1 and 2 best results are usually obtained when the diameter of the liquid distributing disc 12 is from 1.5 to 2.5 times the diameter of the orifice of the pipe 10 and the diameter of the gas deflector disc 11 exceeds that of the liquid distributing disc by about 2 to about 6 cm. The distance between the two discs in this embodiment may vary from a few millimeters to a few centimeters.

In the modification shown in Fig. 3 the liquid distributor and gas deflector comprise streamlined bodies 21 and 22, respectively, having approximately the same maximum diameters and outer surfaces of revolution that converge upstream and downstream away from each other and supported from a bracket 23 by longitudinally streamlined supports 24 and 25. The distributor body is provided with a longitudinal bore 26 into which is fitted the liquid supply pipe 27 which is connected directly to the support 25 and carries the distributor body. The gas deflector 22 has a small protrusion 28 extending toward the orifice of the bore and providing a flat liquid deflecting surface 29 for deflecting the liquid directed against it from the bore back against a flat annular liquid distributing face 30 of the distributor as an annular film at the central part thereof. The liquid then forms a film on the face 30 and debouches beyond the margin thereof. The outside diameter of the flat face 30 preferably exceeds that of the liquid deflecting face 29, as shown, and this face 30 is the liquid distributor proper; beyond the face 30 the body is cut away as shown at 31 to provide an annular, substantially quiescent gas space for the thinning liquid film until the latter reaches the circle 19, at which line it is attacked by the atomizing gas stream 18, disrupted into droplets, and entrained as indicated by 20. The optimum dimensions previously given are applicable also to this embodiment, it being noted that the surface 30 corresponds to the distributing disc 12 and the greatest diameter of the gas deflector 22 corresponds to the

diameter of the disc 11; the spacing between the surfaces 29 and 30 will, however, usually be of the order of a few millimeters.

The two embodiments just described are particularly suitable (although not limited) for operation within a stationary atmosphere forming the atomizing gas through which the atomizer moves to produce a relative velocity. An application of this principle is encountered when biocide liquids are atomized from an aeroplane. The plane need only be equipped with a number of atomizers, say 10 to 20, distributed uniformly over the width of the plane, whilst the movement of the plane causes the air to flow relatively to the atomizers.

As was previously indicated, the stream of atomizing gas will often have to be generated by a separate fan or like blowing device. Such an installation is shown in Fig. 4 which, further, illustrates a modified shape for the surface of the liquid distributor and an arrangement wherein the surface of the distributor is directed downstream. In this view the device comprises a cylindrical casing 32 that may, for example, form the upper part of a drying space or chemical reaction space; it is surmounted by an upwardly convergent hood 33 communicating with a gas supply conduit 34 supplied with a suitable atomizing gas, such as air or some other gas that is to react with the liquid, from a blower 35. The atomizer proper is mounted within the parts 32 and 33 and comprise a pair of streamlined bodies 36 and 37, the latter having a bore 38 connected to a liquid supply pipe 39 and supported through the latter from the casing by radial struts 40. The upper end of the bore is formed as a convergent nozzle to discharge a liquid stream having a uniform flow velocity over the area thereof, and the upstream (upper) face of the body 37 is preferably cut away as indicated at 31 in Fig. 3. The body 36 is supported by struts 41; it forms the gas deflector and also has a part thereof shaped to form the liquid distributor. The latter is, in this embodiment, made separate from the streamlined body although this feature is optional; it has the form of a button 42 having a threaded stem carrying a locknut 43 by which it is fastened to the body 36. The face of the liquid distributor nearer the body 37 forms the distributing surface and is shaped as a surface of revolution coaxial with the bore 38. This surface has a frusto-conical marginal portion 44 which is joined smoothly by a curved portion to a point 45.

In operation, liquid from the pipe 39 is discharged from the nozzle of the bore 38 against the liquid distributing body 42 and distributed by the latter uniformly in different radial directions to form a divergently flowing film thereon. The liquid film, after discharging from the distributor, flows through the annular, substantially quiescent space between bodies 36 and 37 and retains its cohesion while being gradually thinned until it reaches a circle indicated at 19, where it is attacked by the gas stream, disrupted into droplets, and entrained as indicated at 20. The optimum relations between the outer diameters of the body 36, the liquid distributor 42 and the orifice of the bore 38 are as indicated for Figs. 1 and 2.

The various features combined for purposes of illustration in the different views may be substituted individually one for another.

The invention can be applied for many purposes, e. g., for atomizing biocide liquids, liquid

fuel (in liquid fuel burning plants and internal combustion engines), solutions, emulsions or suspensions of solids in liquids to be reduced or dried by evaporation or reacted chemically with the atomizing gas or with a gas or other substances.

We claim as our invention:

1. Method of atomizing liquids into fine droplets comprising the steps of supplying the liquid to be atomized onto an intermediate part of the surface of a liquid distributor and forming thereon a film of said liquid different parts of which have divergent velocities along said surface; flowing the liquid film divergently on said surface; discharging the liquid film from the said surface and flowing the discharged liquid as a diverging film through a substantially quiescent thinning space for a substantial distance to effect a thinning thereof, said liquid film being entirely out of engagement with any solid object after being discharged from said surface; continuing the flow of the thinned film beyond said quiescent thinning space; generating a current of atomizing gas and flowing said current substantially perpendicularly to the thinned film immediately beyond said quiescent thinning space; and engaging the thinned film only after emergence from said quiescent thinning space with said current of atomizing gas and thereby disrupting the thinned film into droplets and entraining said droplets in the current.

2. Method according to claim 1, wherein the film is passed through the thinning space after discharge from said surface of the distributor and prior to engagement with the atomizing gas current for a distance equal to at least half of the distance of movement of said film on the said surface.

3. Method according to claim 1, wherein the distributor is rotationally stationary and said parts of the liquid film are given said divergent velocities along said surface by directing the liquid against the said surface.

4. Method of atomizing liquids into fine droplets comprising the steps of supplying the liquid to be atomized substantially onto the central part of the surface of a liquid distributor, said surface being a surface of revolution with a substantially circular margin, and forming thereon a film of said liquid different parts of which have divergent radial velocities; flowing the liquid film divergently radially outwardly on said surface; discharging the liquid film from said margin of the surface and flowing the discharged liquid as a radially diverging film through a substantially space surrounding said margin for a substantial distance to effect thinning thereof, said liquid film being entirely out of contact with any solid object after being discharged from said surface; continuing the flow of the thinned film beyond said quiescent thinning space; generating a current of atomizing gas and flowing said current substantially perpendicularly to the thinned film as a substantially annular current surrounding said quiescent thinning space; and engaging the thinned film only after emergence from said quiescent thinning space with said annular current of atomizing gas and thereby disrupting the thinned film into droplets and entraining said droplets in the current.

5. Method according to claim 4 wherein the film is passed through the thinning space after discharge from the margin of the said surface of the distributor for a distance equal to at least half of the radial distance of movement of said film on the said surface.

6. Method according to claim 4 wherein the outer diameter of the said quiescent thinning space exceeds the diameter of the margin of the said surface of the distributor by between about 1 cm. and 6 cm.

7. A liquid atomizer for atomizing liquid by means of a current of atomizing gas flowing relatively thereto, comprising: a liquid distributor having a liquid distributing surface with a discharge edge disposed substantially transversely to the direction of relative flow of said current of atomizing gas; means for supplying liquid to be atomized to an intermediate part of said surface, and forming on said surface a film of liquid different parts of which have divergent velocities along said surface; and a gas deflector located upstream from said discharge edge with regard to the direction of flow of said current and extending laterally a substantial distance beyond said edge to provide a substantially quiescent thinning space beyond said edge and downstream from the deflector, the part of said distributing surface adjoining the said discharge edge thereof, extending in directions clear of any body bounding said thinning space whereby a liquid film discharged divergently from said edge must flow as a thinning film beyond said discharge edge for said substantial distance entirely out of contact with any solid object before being engaged and disrupted by said current of atomizing gas.

8. A liquid atomizer according to claim 7, wherein the deflector extends laterally beyond the discharge edge of the liquid distributing surface for a distance between about 0.5 cm. and 3 cm.

9. A liquid atomizer according to claim 7, wherein the liquid distributor is stationary with respect to the atomizer as a whole.

10. A liquid atomizer according to claim 7, wherein the liquid distributor is stationary with respect to the atomizer as a whole and the means for supplying liquid onto the surface thereof comprises a liquid supply conduit having an outlet orifice directed toward the said intermediate part of the liquid distributing surface.

11. A liquid atomizer according to claim 7, wherein the liquid distributor is stationary with respect to the atomizer as a whole and the said means for supplying liquid onto the surface thereof comprises a liquid supply conduit having a flow passage opening through the liquid distributing surface for discharging liquid in a direction away from said surface, and a liquid deflector in spaced relation to said liquid distributing surface and opposite said flow passage for deflecting the liquid back against the liquid distributing surface.

12. A liquid atomizer for atomizing liquid by means of a current of atomizing gas flowing relatively thereto, comprising: a liquid distributor having a liquid distributing surface with a substantially circular discharge edge disposed substantially transversely to the direction of relative flow of said current of atomizing gas; means for supplying liquid to be atomized substantially to the central part of said surface and forming on said surface a film of liquid different parts of which have divergent radial velocities; and a gas deflector having a substantially circular outline located upstream from said discharge edge with regard to the direction of flow of said current and extending radially a substantial distance beyond said edge to provide an annular, substantially quiescent thinning space surrounding said edge and downstream from the gas deflector, the part of said distributing surface adjoining the said discharge edge thereof extending in directions

clear of any body bounding said thinning space, whereby a liquid film discharged radially divergently from said edge must flow as a thinning film beyond said discharge edge for said substantial distance entirely out of contact with any solid object before being engaged and disrupted by said current of atomizing gas.

13. A liquid atomizer according to claim 12 wherein said deflector is in the shape of a streamlined body having an outer surface that converges upstream and having, in combination therewith, a second streamlined body spaced downstream from the deflector to form a downstream wall for said quiescent thinning space, said second body having an outer diameter extending radially outwardly at least as far as said deflector.

14. A liquid atomizer according to claim 12 wherein said deflector has a diameter equal to at least 1.5 times the diameter of said discharge edge of the distributing surface.

15. A liquid atomizer according to claim 12 wherein said deflector has a diameter that exceeds the diameter of said discharge edge of the distributing surface by between about 1 cm. and 6 cm.

16. A liquid atomizer according to claim 12 wherein the means for supplying the liquid to the distributing surface comprises a supply conduit having an orifice with the axis thereof substantially at the center of said surface and perpendicular thereto, the diameter of said discharge edge being between about 1.5 and 2.5 times the diameter of said orifice.

17. A liquid atomizer for atomizing liquid by means of a current of atomizing gas flowing relatively thereto comprising: a stationary liquid distributor having a liquid distributing surface with a substantially circular discharge edge disposed substantially transversely to the direction of relative flow of said gas current, said surface being a surface of revolution; means for supplying liquid to be atomized substantially to the central part of said surface and forming on said surface a film of liquid different parts of which have divergent

radial velocities comprising a liquid supply conduit having a discharge orifice with the axis thereof substantially coincident with the axis of said surface of revolution; and a gas deflector 5 having a substantially circular outline located upstream from said discharge edge with regard to the direction of flow of said current and extending radially beyond said edge for a distance between about 0.5 cm. and 3 cm. to provide an 10 annular, substantially quiescent thinning space surrounding said edge and downstream from the gas deflector, the part of said distributing surface adjoining the said discharge edge thereof extending in directions clear of any body bounding said 15 thinning space, whereby a liquid film discharged radially divergently from said edge must flow as a thinning film beyond said discharge edge for a distance between about 0.5 cm. and 3 cm. entirely out of contact with any solid object before 20 being engaged and disrupted by said current of atomizing gas.

18. A liquid atomizer according to claim 17 wherein said liquid distributing surface is a flat disc and the diameter of said discharge edge is 25 between about 1.5 and 2.5 times the diameter of said orifice.
